VOUCHER AND CHECK FILE GUIDE AND
DETACHABLE TAB

Harry L. Cowden, Guthrie Center, Iowa

Application February 24, 1931. Serial No. 517,836

10 Claims. (Cl. 129—16.8)

My invention relates to voucher and check files, letter files, card index files, and the like.

My objects are to provide a tab which can be attached to and detached from a guide card having proper facilities for its reception and retention; to provide facilities in said tab wherein name cards or other index slips can be inserted or withdrawn; and to provide a guide card having facilities for the reception and retention of said tab. Other objects will appear as the description progresses.

Figure 1 represents a front elevation of the tab; Fig. 2, a plan view of Fig. 1; Fig. 3, a vertical cross section on the line 3—3 in Fig. 1; Fig. 4, a vertical cross section on the line 4—4 in Fig. 1; and Fig. 5, a perspective view showing the guide card with the tab mounted thereon, the transparent flap being removed. The drawing is for illustrative purposes and, therefore, Figs. 1 to 4 are drawn to an enlarged scale.

Although I show the preferred embodiment of my invention, I do not thereby limit myself to the precise details shown, but wish it understood that, within the scope of what hereinafter is claimed, various changes in the size, shape and other details of construction may be made, without departing from the spirit of the invention.

The guide card 1 is provided with a series of perforations 2 arranged longitudinally of said card.

The tab is formed of an integral piece of sheet metal. The main body portion 3, hereinafter called the plate, is provided with a pair of hooks 4—5, a rigid tongue 6 and a flexible tongue 7 provided with a shoulder 7a. The upper portion of the plate 3 is formed into a name card holder 8 containing a depressed portion 9. The upper edge of the name card holder is hemmed and one edge of a transparent celluloid flap 10 is secured tightly in said hem.

The hooks 4—5 are hooked over the top edge of the guide card 1, the tongue 6 disposed through a perforation 2, and the plate 3 moved so as to clip the guide card. When the lip 6 reaches the limit of its longitudinal travel, the shoulder 7a snaps into the perforation and acts as a stop which prevents the tongue 6 from slipping back. The tab is detached from the guide card by pushing shoulder 7a out of the perforation, sliding tongue 6 back far enough to clear the card 1, and lifting hooks 4—5 free. A plurality of perforations are provided so as to afford a variety of locations for the tab.

The celluloid flap is raised enough to permit insertion or withdrawal of a name card or other

index card, and when released, the flap lays over the name card and protects it from dirt as well as keeping it in place. The depressed portion 9 holds the name card from escaping edgewise.

The device is particularly useful in banks and offices where each customer must have a pocket or file for his checks or vouchers. It is, however, useful in ordinary letter files and card index files. The guide card 1 may be of any size, depending upon the file in which it is used, and any number of perforations may be provided to suit the filing system.

Having thus described my invention, what I claim as new and desire to secure by Letters Patent is:

1. A tab of the class described comprising a plate provided with a rigid tongue, and a flexible tongue having a shoulder, said plate being adapted to be mounted on a file guide containing perforations, so that said rigid tongue and said shoulder extend through a single perforation in said file guide, the rigid tongue acting as a clip and the shoulder on the flexible tongue acting as a stop to prevent said rigid tongue from slipping back; a pair of hooks on said plate adapted to hook over the top edge of said guide. 75

2. A tab of the class described comprising a plate provided with a rigid tongue, and a flexible tongue having a shoulder, said plate being adapted to be mounted on a file guide containing perforations, so that said rigid tongue and said shoulder extend through a single perforation in said file guide, the rigid tongue acting as a clip and the shoulder on the flexible tongue acting as a stop to prevent said rigid tongue from slipping back; a pair of hooks on said plate adapted to hook over the top edge of said guide; a name card holder on the top edge of said plate. 80

3. A tab of the class described comprising a plate provided with a rigid tongue, and a flexible tongue having a shoulder, said plate being adapted to be mounted on a file guide containing perforations, so that said rigid tongue and said shoulder extend through a single perforation in said file guide, the rigid tongue acting as a clip and the shoulder on the flexible tongue acting as a stop to prevent said rigid tongue from slipping back; a name card holder, provided with a depressed portion, on the top edge of said plate. 95

4. A tab of the class described comprising a plate provided with a rigid tongue, and a flexible tongue having a shoulder, said plate being adapted to be mounted on a file guide containing perforations, so that said rigid tongue and said shoulder extend through a single perforation in 100

- 45 said file guide, the rigid tongue acting as a clip and the shoulder on the flexible tongue acting as a stop to prevent said rigid tongue from slipping back; a pair of hooks on said plate adapted to hook over the top edge of said guide; a name card holder on the top edge of said plate.

50 5. A tab of the class described comprising a plate provided with a rigid tongue and a flexible tongue having a shoulder, said plate being adapted to be mounted on a file guide containing perforations, so that said rigid tongue and said shoulder extend through a single perforation in said file guide, the rigid tongue acting as a clip and the shoulder on the flexible tongue acting as a stop to prevent said rigid tongue from slipping back; a name card holder on the top edge of said plate; a transparent flap mounted on said name card holder.

55 6. A tab of the class described comprising a plate provided with a rigid tongue, and a flexible tongue having a shoulder, said plate being adapted to be mounted on a file guide containing perforations, so that said rigid tongue and said shoulder extend through a single perforation in said file guide, the rigid tongue acting as a clip and the shoulder on the flexible tongue acting as a stop to prevent said rigid tongue from slipping back; a pair of hooks on said plate adapted to hook over the top edge of said guide; a name card holder, provided with a depressed portion, on the top edge of said plate.

60 7. A device of the class described comprising a file guide containing a row of perforations arranged longitudinally of said guide; a plate provided with a rigid tongue, and a flexible tongue having a shoulder, said plate being mounted on said guide so that said rigid tongue and said shoulder extend through one of said perforations, the rigid tongue acting as a clip and the shoulder on the flexible tongue acting as a stop to prevent the rigid tongue from slipping back; a name card holder on the top edge of said plate.

65 8. A device of the class described comprising a file guide containing a row of perforations arranged longitudinally of said guide; a plate provided with a rigid tongue, and a flexible tongue having a shoulder, said plate being mounted on said guide so that said rigid tongue and said shoulder extend through one of said perforations, the rigid tongue acting as a clip and the shoulder on the flexible tongue acting as a stop to prevent the rigid tongue from slipping back; a pair of hooks on said plate adapted to hook over the top edge of said guide; a name card holder, provided with a depressed portion, on the top edge of said plate; a transparent flap disposed over said depressed portion and secured to said name card holder.

70 9. A device of the class described comprising a file guide containing a row of perforations arranged longitudinally of said guide; a plate provided with a rigid tongue, and a flexible tongue having a shoulder, said plate being mounted on said guide so that said rigid tongue and said shoulder extend through one of said perforations, the rigid tongue acting as a clip and the shoulder on the flexible tongue acting as a stop to prevent the rigid tongue from slipping back; a name card holder on the top edge of said plate; a transparent flap mounted on said name card holder.

75 10. A device of the class described comprising a file guide containing a row of perforations arranged longitudinally of said guide; a plate provided with a rigid tongue, and a flexible tongue having a shoulder, said plate being mounted on said guide so that said rigid tongue and said shoulder extend through one of said perforations, the rigid tongue acting as a clip and the shoulder on the flexible tongue acting as a stop to prevent the rigid tongue from slipping back; a name card holder on the top edge of said plate.
